UNITED STATES PATENT OFFICE.

HARRY M. SPRECHER, OF EPHRATA, PENNSYLVANIA.

WINDING-MACHINE.

1,076,920.

Specification of Letters Patent.

Patented Oct. 28, 1913.

Application filed August 13, 1912. Serial No. 714,938.

To all whom it may concern:

Be it known that I, HARRY M. SPRECHER, a citizen of the United States, residing at Ephrata, in the county of Lancaster and State of Pennsylvania, have invented new and useful Improvements in Winding-Machines, of which the following is a specification.

This invention relates to winding machines, the same being especially adapted for dispensing wire and similar fabric, such as fencing, so that any desired portion of a roll of fabric may be unwound therefrom and simultaneously wound into an individual roll to be delivered to the purchaser.

A further object of the invention is to provide a novel form of winding shaft which will permit the portion of the roll contained thereon to be readily removed as soon as it is severed from the main roll.

A further object of the invention is to provide a device of the character referred to which is adjustable to rolls of different lengths.

With the above and other objects in view, the invention consists in the construction, combination and arrangement of parts, as will be hereinafter more fully described, illustrated in the accompanying drawings, and pointed out in the claims hereunto appended.

In the drawings: Figure 1 is a perspective view of a winding machine embodying the present invention. Fig. 2 is a vertical cross section through the same. Fig. 3 is a plan view of one end of the machine. Fig. 4 is an enlarged cross section through the winding roller, showing the pins retracted. Fig. 5 is a similar view of the roller, showing the pins projected.

While the invention hereinafter described is capable of a number of embodiments, a simple embodiment thereof is illustrated in Fig. 1, wherein the supporting frame of the device or machine is shown as composed of a pair of posts 1 and 2 located at a suitable distance apart and provided with bases 3 adapting said posts to be firmly secured to the floor. The posts are connected a suitable distance above the floor by a horizontal cross rail 4, upon which is mounted a pair of brackets 5, each provided at its outer end with an inwardly projecting tapering bearing 6 adapted to be inserted in one end of a roll of fabric, such as is shown at 7, the two brackets at opposite ends of the roll

thus forming a support which will hold the roll 7 and at the same time permit said roll to revolve in unrolling the fabric therefrom, in the manner illustrated in Fig. 1. Each of said brackets 5 is provided, adjacent to its rear end, with a slot 6' adapting it to fit over and slide lengthwise of the rail 4, for the purpose of adjustment. Each bracket is further provided with a binding screw 8, so as to hold the bracket in place, after it has been adjusted to the proper point along the rail 4, in accordance with the roll 7. Secured to the posts 1 and 2, adjacent to the top thereof, are stirrups 9 adapted to form a support for a revolving winding shaft, hereinafter particularly described. In the preferred embodiment of the invention, each of said stirrups 9 is fixedly secured to the post and connected with the main body of the stirrup by a hinge pin 11 which will enable the stirrup to be folded backward when not in use, and after the winding shaft has been removed therefrom.

The winding shaft, as illustrated in Figs. 4 and 5, comprises an outer tubular shell 12, and an inner core 13 which is also preferably tubular, but not necessarily so. The inner core 13 is of considerably less diameter than the shell 12, and is supported centrally within the shell by means of webs 14 arranged at suitable intervals along the length of the shell, within which they are secured, the said webs being recessed or cut away at one side, as shown at 15, to permit the core 13 to slide transversely or radially within the outer shell from a central position to an eccentric one, as indicated in the two detail sections, Figs. 4 and 5. Connected to the inner core, at any suitable number of intervals throughout the length thereof, are fabric engaging pins 16, which are curved, as shown in Figs. 4 and 5, and which are adapted to project through corresponding slots 17 formed in the outer shell. By curving the pins 16, it will be seen that as the inner core 13 is partially turned by means of an operating hand crank 18 at one end thereof, the concaved sides of the pins working against the ends of the slots 17 will cause said pins to be projected outwardly beyond the outer surface of the shell 12, and correspondingly when said core is turned in the opposite direction, the convex sides of the pins will operate against the opposite ends of the slots 17, so as to

cause said pins to be retracted within the plane of the periphery of the shell.

The operation of the device is well illustrated in Fig. 1, wherein it will be observed that after placing the roll 7 on the brackets 5, the crank 18 is given a partial turn which causes the pins 16 to project outwardly through the slots 17, assuming the position illustrated in Fig. 5. The fabric is then engaged over said pins 16 and the hand crank 18 is then operated, until the desired amount of fabric is unwound from the roll 7, and wound upon the upper winding shaft of the device. The fabric is then severed between 10 the two rolls, after which by reversing the direction of movement of the crank 18 for a portion of a turn, the pins 16 are retracted entirely within the outer shell 12 of the winding shaft, thus enabling the roll on the 15 winding shaft to be easily slid longitudinally off the end of said shaft, after removing the latter or one end thereof from the stirrup or stirrups 9.

What is claimed is:

- 25 1. A winding machine, comprising a supporting frame, a winding shaft embodying a core, a tubular shell surrounding the core and movable transversely thereon, and retractable pins projecting from the core 30 through openings in the shell and serving also as a driving medium by which the rotary movement of the core is imparted to the shell.
- 35 2. A winding machine, comprising a supporting frame, and a winding shaft embodying a tubular shell, a core movable within the shell, and retractable pins projecting from the core through openings in the shell, the core having a movement trans-

versely within the shell to project and retract the pins, such transverse movement being produced by the coöperative engagement of the pins with the shell. 40

3. A winding machine, comprising a supporting frame, and a winding shaft embodying a tubular shell, a core movable within the shell, and retractable pins projecting from the core through openings in the shell, the core having both a partial 45 rotary and transverse movement within the shell to project and retract the pins, such transverse movement being produced by the coöperative engagement of the pins with the shell.

4. A winding machine, comprising a supporting frame, and a winding shaft embodying a tubular shell, a core movable within the shell, and curved pins projecting from the core through openings in the shell and coöperating at their concaved 50 sides with the shell to effect the projection of the pins beyond the outer surface of the shell.

5. A winding machine, comprising a supporting frame, and a winding shaft embodying a tubular shell, a core movable within the shell, and curved pins projecting from the core through openings in the shell and coöperating at their convex 55 sides with the shell to effect the retraction of the pins within the outer surface of the shell.

In testimony whereof I affix my signature in presence of two witnesses.

HARRY M. SPRECHER.
